HANGER FOR RADIATORS

Bernard I. Downs, Forestville, Conn., assignor to
 The Vulcan Radiator Company, Hartford,
 Conn., a corporation of Connecticut

Application December 7, 1949, Serial No. 131,637

3 Claims. (Cl. 257—163)

1

This invention relates to a radiator and more particularly to baseboard radiators which commonly contain a heat transfer unit including a tube having a plurality of spaced fins thereon.

An object of this invention is to provide a baseboard radiator which is easy to install and which includes a novel hanger that will permit the heat transfer unit thereof to be easily adjusted for height, or level, as may be desired.

It is a further object of this invention to provide a hanger for baseboard radiators which is simple in construction, durable and easy to manufacture.

Further objects and advantages of this invention will be more clearly understood from the following description and from the accompanying drawings in which:

Fig. 1 is an end view, partially in section, illustrating my improved radiator hanger.

Fig. 2 is a front view thereof.

Fig. 3 is a view similar to Fig. 1, but illustrating the manner in which my improved hanger is installed.

Fig. 4 is an end view, partly in section, illustrating the use of my improved radiator hanger with a back plate of modified form.

Fig. 5 is a fragmentary front view showing a further modified form of back plate.

Fig. 6 is a fragmentary side view, partly in section, illustrating another form of my improved hanger construction.

As shown in the drawings, the numeral 5 denotes the lower portion of the wall of a room which is adjacent to the floor indicated at 6.

A conventional baseboard radiator for which my invention is particularly adapted includes a heat transfer unit comprising a heat conductor in the form of a tube 7 which has a plurality of spaced vertically disposed fins 8 thereon.

The said baseboard radiator also commonly includes a back plate 9 which is preferably secured to the wall portion 5 by fastening means, such as nails or screws, indicated at 10; the said plate has an upwardly extending lip 11 formed along the free edge thereof and spaced from the wall portion to provide a support for the cover of the radiator which is not shown herein.

The present invention provides a hanger for the said heat transfer unit which includes a member 12 that is preferably constructed of a single piece of wire and formed to provide a straight front portion 13 having an angled upper portion 14 extending therefrom with a hook portion 15 projecting perpendicularly to the end of the said angled portion. The front portion

2

of said member is bent rearwardly to provide an offset portion 16 with a vertical portion 17 extending downwardly therefrom which is adapted to be disposed upon the vertical axis of the heat transfer unit.

The upper portion of the back plate 9 is provided with a hollow boss 18 which projects outwardly therefrom and has an opening 19 through which the hook portion 15 projects to engage the lower edge of said opening for securing the hanger to the back plate, in the position illustrated in Fig. 1, and thereby support the heat transfer unit.

When the said heat transfer units are mounted, it is desirable that they be adjusted so that they are disposed parallel to the floor 6. In some cases, it is also desirable to have the tube 7 of the unit slightly on an incline to permit drainage of liquid therefrom. For this purpose, the portion 17 of the hanger is threaded to receive a suitable nut 20, preferably of the sheet metal type known as a "speed nut," which has opposed prongs 21 adapted to engage the screw thread on the portion 17 and adjustably position the said nut to abut the lower free edges of adjacent fins 8 and thereby support the entire unit.

The manner of mounting a baseboard heat transfer unit with my improved bracket is illustrated in Fig. 3 wherein the said unit may be first positioned at the desired height from the floor by means of temporary blocks 22 by which it is supported in the desired position. The hook portion 15 of the hanger is then inserted into the opening 19 and the hanger is swung downwardly between adjacent fins 8 until the portion 13 abuts the side of the tube 7 wherein it will be in the position illustrated in Fig. 1. A nut 20 is then slid upwardly on the threaded portion 17 until it engages the bottom edges of the fins, as shown in Fig. 2, wherein it will be noted that the said nut is of sufficient length to engage a plurality of the fins and thereby distribute the weight of the heating unit therebetween. If desired, a conventional nut and washer may be used in lieu of the nut 20 on the portion 17.

It will be noted that my improved hanger may be readily attached to the back plate and manipulated from the front of the heat transfer unit without requiring the use of screws or the like such as commonly required with radiator brackets heretofore used wherein it has been necessary for the operator to support the said unit with one hand while attempting to secure

the bracket to the wall in back of the said heating unit with the other hand. Such an operation has been exceedingly difficult due to the low position of the heating unit which has rendered it necessary for the operator to work in a prone position on the floor.

In the form illustrated in Fig. 4, the back plate 9-a has an angled portion 24 which underlies a border strip 25 that is secured to the wall studs 26 to provide a border for the plaster 27. In this form, the holes 15-a are located in the said angled portion and receive the hook 15 of the wire member 12.

In the form shown in Fig. 5, the back plate 9-b is provided with an elongated raised rib 18-b which runs for the full length of the strip and the holes 15-b are contained in said rib in the same manner as in the circular bosses of Figs. 1 to 3. This elongated rib provides a stiffening for the plate 9-b which strengthens the support for the hanger.

In the form illustrated in Fig. 6, the opening 15-c, which receives the hook portion 15 of the hanger, is provided directly in an elongated wall member 25-c which may be in the form of a border strip for the plaster 27. In this form, a hook strip 11-c may be provided directly above the row of openings 15-c to support the radiator cover.

If desired, it is possible to use my improved radiator hanger with an opening that may be drilled directly in the wall or any other convenient portion thereof to receive the hook portion 15 of the supporting member.

I claim:

1. The combination of a heat transfer unit which includes a tube having a plurality of spaced fins thereon, a supporting element for said unit having an opening therein, and a hanger for said unit including a hook portion inserted into said opening, a supporting portion extending downwardly from the hook portion and between the said fins, and means on said hanger engaging the bottom edges of adjacent fins for supporting the said unit.

2. The combination of a heat transfer unit

which includes a tube having a plurality of spaced fins thereon, a supporting member secured to a wall and having an opening therein located above the said fins, and a hanger for said unit having a hook portion inserted into said opening, a supporting portion extending downwardly from the hook portion and between the fins to a point below the bottom edges of said fins, and means adjustably secured adjacent the lower end of said supporting portion and engaging the bottom edges of adjacent fins for adjustably supporting the said unit.

3. The combination of a heat transfer unit which includes a tube having a plurality of spaced fins thereon, a back plate adapted to be positioned adjacent to a wall and having a forwardly extending projection and an opening in said projection located above the top of said unit, and a hanger for said unit having a hook portion inserted into said opening, a supporting portion extending downwardly from the hook portion, between the fins, and in front of the tube to a point below the bottom edges of said fins, and laterally extending means secured to said supporting portion and engaging the bottom edges of adjacent fins for supporting said unit.

BERNARD I. DOWNS.
